DESIGN FOR A STORAGE BATTERY CASE

Willard L. Reinhardt, Shaker Heights, Ohio, assignor to Willard Storage Battery Company, Cleveland, Ohio, a corporation of West Virginia

Application February 23, 1937, Serial No. 67,801

Term of patent 14 years

To all whom it may concern:

Be it known that I, Willard L. Reinhardt, a citizen of the United States and a resident of Shaker Heights, in the county of Cuyahoga and State of Ohio, have invented a new, original, and ornamental Design for a Storage Battery Case, of which the following is a specification, reference being had to the accompanying drawing, forming a part thereof, in which

Fig. 1 is a perspective view of a storage battery case showing my new design, the shading showing the sides and the ends depressed; and

Fig. 2 is a bottom view of the same, this view also showing that the sides and the ends are depressed with respect to the corners of the case.

The side and end portions not shown in the drawing are of the same design as those shown.

I claim:

The ornamental design for a storage battery case substantially as shown and described.

WILLARD L. REINHARDT.
